HOMER J. YOUNG, OF DAYTON, OHIO.

COMBINATION CLARIFIER AND SEPARATOR.

1,294,017.

Specification of Letters Patent. Patented Feb. 11, 1919.

Application filed February 25, 1918. Serial No. 218,987.

To all whom it may concern:

Be it known that I, HOMER J. YOUNG, a citizen of the United States, residing at Dayton, in the county of Montgomery and State of Ohio, have invented certain new and useful Improvements in Combination Clarifiers and Separators, of which the following is a specification.

This invention relates to new and useful improvements in combination clarifiers and separators.

One object of the invention is to provide means for readily and quickly converting a clarifier into a separator, and vice versa.

15 This obviates the necessity of providing two machines, one for clarifying and the other for separating the milk, to the end that a great saving is effected.

Another object of the invention is to provide a revoluble bowl shiftable on the vertical spindle as a seat, to automatically bring the center of gyration into coincidence with the center of mass for any speed of rotation. It is a broad and well known principle that

25 the center of mass must coincide with the center of gyration in high speed machinery. When they do not coincide in a separator or clarifier, we have the chatter caused by the jerky engagement between the worm on a

30 shaky spindle, and the gear with which it meshes. It is the object of my invention to eliminate this chatter by substituting for the top flexible spindle bearing of other constructions, a mounting which permits the 35 bowl to automatically shift on the spindle to bring the center of mass into coincidence with the center of gyration at all speeds, which insures a smoothly running bowl at all times.

40 A further object of the invention is to provide centrifugal means for preventing the revoluble bowl from being raised above the spindle during its rapid rotation. In other machines, the weight of the bowl is

45 excessively heavy because gravity must hold it upon the spindle during its rapid revolution. In my construction, on the other hand, centrifugal pawls are employed to prevent the bowl from flying off, without interfering with the self-balancing of the latter, and therefore the weight of the bowl may be reduced approximately one half, effecting

a corresponding reduction in the power required to turn it. For example, since the rotation of the bowl to that of the handle, 55 is ordinarily in the proportion of 100 to 1, every pound of weight taken off the bowl results in 100 pounds of turning power being taken off the handle. My improved construction, therefore, results in a material reduction in the power required to turn the bowl, which is an important item in the clarifying and separating art.

A further object of the invention is to provide a clarification chamber in the bowl 65 that is preferably hook-shaped in cross section, to receive dirt, hair, manure, waste tissue and other foreign matter thrown off from the milk when the machine is used as a separator. This matter will lodge in 70 said chamber, from which it cannot escape, since the contour of the latter forms a pocket to prevent its upward movement with the skim milk, while centrifugal force opposes any tendency it has to work outwardly toward the disks.

Other important and incidental objects will be brought out in the following specification, and particularly set forth in the subjoined claims.

The preferred form of embodiment of my invention is illustrated in the accompanying drawings, of which Figure 1 is a vertical sectional view of my combination clarifier and separator. Fig. 2 is an elevational view 85 of the upper end of the spindle and the lower end of the bowl, showing my improved mounting for the latter. Fig. 3 is a bottom view of the bearing which screws in the lower end of the bowl. Fig. 4 is a perspective view of the nut employed at the upper end of the bowl when the machine is used as a separator. And Fig. 5 is a perspective view of the nut employed when the machine is operated as a clarifier.

Throughout the specification and drawings, similar reference characters denote corresponding parts.

In a detailed description of the preferred form of embodiment of my invention, the 100 numeral 1 designates a revoluble bowl having a sloping top 2 and a body portion comprising a vertical side wall 3. The lower rim of the latter rests upon a rubber gasket

3^a supported by the upper rim of an outwardly bulging corner portion 4 preferably hook-shaped in cross section for a purpose to be hereinafter described. After extending inwardly a short distance, the bottom portion of the bowl inclines upwardly to a tubular central portion the lower end of which is threaded to receive a cylindrical member 5 which terminates in an outwardly and downwardly extending portion 6 that is cored out to form an inwardly tapering bore 7 whose extreme inner end is rounded to semi-elliptical form in cross section. This bore 7 is adapted to receive the top 8 of a vertical spindle 9, said top being preferably semi-circular in cross section.

The top of the bore 7 is rounded as shown in Figs. 1 and 2, to provide ample room for the center of mass to seek the center of gyration as the bowl is revolved by the spindle 9. If the center of mass and gyration are at a variance, or contend with each other during the rapid rotation of the bowl, the spindle will have a shaky rotation which produces the chatter in the worm and gears so commonly heard in separators. But in my improved mounting the center of mass will automatically seek the center of gyration, since the dome-shaped end of the bore 7 so cooperates with the top of the spindle, that during its rotation the bowl will automatically shift on the latter as a seat until the center of gyration coincides with the center of mass at all speeds, whereupon it will turn evenly and smoothly without producing any chattering sounds. In all other separators with which I am familiar, the top bearing of the spindle is necessarily a flexible one, with springs. This is an unmechanical construction which my invention obviates by providing in its place rigid spindle bearings.

Pivoted secured by a pin 10 in two oppositely countersunk portions of the upper end of the spindle 9, just below its rounded top 8, are the lower ends of two oscillatory, upwardly-tapering wings 11 through which, and a slot 12 in the upper end of the spindle 9, a transverse pin 13 extends. This pin is fixedly secured to each of the wings 11, through which it projects, but is adapted to oscillate within the slot 12 in the spindle 9 for a purpose to be soon described.

Each end of the pin 13 extends loosely into a groove 14 provided in the downwardly extending portion 6 of the member 5, primarily to turn the bowl 1 when the spindle 9 is revolved. By virtue of the grooves 14, the bowl 1 is permitted to shift laterally in the direction of the length of the pin 13 whose ends loosely extend into said grooves, or the pin may shift laterally through the slot 12 in the spindle, said movements of the bowl or pin serving to provide a form of universal joint between the bowl and spindle 65 without interfering with the latter's pri-

mary function of revolving the bowl, but at the same time permitting the bowl to shift on the top of the spindle as a seat to seek a point where the center of gyration coincides with the center of mass at all speeds. (See Figs. 1, 2 and 3.)

For the purpose of preventing the bowl being lifted from the spindle during its rapid rotation, the ends of the pin 13 are adapted to be engaged by the upper ends of pawls or dogs 15 pivoted within the grooves 14. The lower ends of these pawls are weighted to hold their upper ends normally out of the path of the ends of the pin 13. However, during a rapid rotation of the bowl, the lower ends of the pawls 15 will be thrown outwardly by centrifugal force to bring their upper ends below the extremities of the pin 13 as shown in Fig. 1, and thereby prevent the bowl being lifted from the spindle during its rapid rotation.

In other constructions gravity alone is relied upon to prevent the bowl being raised from the spindle. This necessitates an increase in the weight of the bowl and a proportionate increase in turning power, both of which I materially reduce by employing the centrifugal pawls to prevent the bowl being lifted from the spindle during its rapid rotation.

Attached to vertical ribs 16 secured to the exterior wall of the tubular shell 17 at the center of the bowl, is a series of downwardly inclined disks 18, preferably seven in number. The ribs 16 are hollow to receive from the tubular shell 17, through slots 19 formed therein, the whole milk which is delivered to the bowl from the bottom of the ribs between the inclined bowl floor and a disk 20 that is an outwardly projecting integral part of the supporting shell for the other disks.

In Fig. 1 the bowl is shown arranged to separate the incoming milk. Referring to this figure, the numeral 21 designates a collar which is threaded on the upper end of the tubular shell 17. This collar contains vertical cream passages 22 which communicate, through an annular base portion 22^a, with the space between the ribs 16 to receive therefrom the cream which has worked into it from between the disks 18, said cream being emitted from the passages 22 through outlet ports 23.

Adapted to be screwed on the lower portion of the collar 21, is a nut 24 which has curved ports 25 extending from its side periphery to its bottom portion, for communication with the space between the uppermost disk 18 and the inclined top 2 of the bowl, to receive therefrom the skim milk which travels upwardly to it along the inside periphery of the bowl shell. This nut 24 also serves to press the upper portion of the bowl shell tightly against the rubber

gasket 3^a to form a tight connection between the upper and lower parts of the bowl.

When used as a separator, the skim milk, being heavier than the cream, is thrown outwardly by centrifugal force against the inside periphery of the bowl, whence it finds its way upwardly along said periphery to the skim milk outlet port 25 in the nut 24. The cream, on the other hand, is gradually forced inwardly between the disks 18 into the space between the ribs 16, whence, after passage through the annular portion 22^a, it enters the passages 22 and is discharged therefrom through the outlet ports 23. (For the path of the incoming whole milk, and the cream and skim milk discharged therefrom, see the arrows in Fig. 1.) During the separation of the whole milk, the dirt, manure, waste tissue and other foreign particles separated therefrom, will lodge in the clarification chamber 27, to be held there by its curved top against escape with the skim milk and prevented by centrifugal force from working inwardly with the cream. It will therefore be seen that my device is adapted to act as a clarifying separator.

When it is desired to use the machine solely as a clarifier, the ported nut 24 is removed from the collar 21, and a solid non-ported nut 26 applied to the latter in its place. The nut 26 will afford no outlet for the skim milk; hence said milk, together with the cream, will find its outlet through the passages 22 and ports 23 after being clarified. It might be stated here, for explanatory purposes, that when the incoming whole milk is clarified, the bowl is revolved at a slower rate of speed than during the process of separation, since less centrifugal force is required to discharge foreign matter from the whole milk, than to separate cream therefrom. When the bowl containing the whole milk is revolved at this reduced speed, the particles of dirt, manure, waste tissue and other foreign matter which it contains, will be separated from it by centrifugal force and lodged in the clarification chamber 27 which will retain it until removed.

It will thus be seen that I have provided convenient and efficient means for converting a clarifier into a separator, and vice versa, thus effecting a saving in the cost of an additional machine for performing either one of these functions.

I do not wish to be limited to the details of construction and arrangement herein shown and described, and any changes or modifications may be made therein within the scope of the subjoined claims.

Having described my invention, I claim:

1. In a device of the type specified, the combination with a vertical spindle having a head semi-circular in cross section, of a revoluble bowl, a member extending down-

wardly from the central portion of said bowl, and an inwardly tapering central bore in said member to loosely receive the upper end of said spindle, the inner end of said bore being rounded to semi-elliptical form 70 in cross section, to provide ample room for the revoluble bowl to shift on the top of the spindle as a seat, to seek a point where the center of gyration coincides with the center of mass.

2. In a device of the type specified, the combination with a vertical spindle, of a revoluble bowl, a member extending downwardly from the central portion of said bowl, an inwardly tapering central bore in said member to loosely receive the upper end of said spindle, and a horizontal element loosely extensible through a lateral slot in the upper end of the spindle, into grooves provided in said downwardly extending member, for the purpose of turning the bowl and at the same time permitting it to shift on the top of the spindle as a seat to seek a point where the center of gyration coincides with the center of mass. 90

3. In a device of the type specified, the combination with a vertical spindle, of a revoluble bowl, a member extending downwardly from the central portion of said bowl, an inwardly tapering central bore in said member to loosely receive the upper end of said spindle, a horizontal pin loosely extensible through a lateral slot in the upper end of the spindle, into grooves provided in said downwardly extending member, and oscillating wings pivotally secured at their lower ends to the spindle and through whose upper ends said horizontal pin tightly passes, to firmly hold it during its movement through the slot and the movement of the bowl in the direction of its length, for the purpose described. 100

4. In a device of the type specified, the combination with a vertical spindle, of a revoluble bowl, a member extending downwardly from the central portion of said bowl, an inwardly tapering central bore in said member to loosely receive the upper end of said spindle, a pair of oppositely disposed projections on the upper end of the spindle, extensible into grooves in said downwardly extending member, to turn the bowl when the spindle is rotated, and centrifugal means mounted within said grooves, adapted to engage said projections during the rapid rotation of the bowl, to prevent the latter being raised above the upper end of the spindle. 115

5. In a device of the type specified, the combination with a vertical spindle, of a revoluble bowl, a member extending downwardly from the central portion of said bowl, an inwardly tapering central bore in said member to loosely receive the upper end of said spindle, a pin extending through the 125

upper end of said spindle into grooves in
said downwardly extending member, and
centrifugal pawls pivotally secured within
said grooves, the upper ends of said pawls
5 adapted to be forced under the ends of said
pin to prevent the bowl being thrown off
the spindle, when the lower ends of said

pawls are thrown outwardly by centrifugal
force during a rapid rotation of said bowl.

In testimony whereof I have hereunto set 10
my hand this 23rd day of February, 1918.

HOMER J. YOUNG.
